UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

ROCK-DRILLING MECHANISM.

Application filed July 1, 1921. Serial No. 481,974.

To all whom it may concern:

Be it known that I, ELMER G. GARTIN, a citizen of the United States, residing at Claremont, in the county of Sullivan and 5 State of New Hampshire, have invented certain new and useful Improvements in Rock-Drilling Mechanisms, of which the following is a full, clear, and exact specification.

My invention relates to rock drilling 10 mechanisms, and more particularly to improved feeding mechanisms for use therewith.

The object of my invention is to provide an improved rock drilling mechanism. An 15 other object of my invention is to provide an improved feeding mechanism of general application and provided with novel and improved controlling means. A further object of my invention is to provide an improved controlling means for pressure fluid feeding mechanisms especially adapted for use in rock drilling operations and comprising control means located in juxtaposition to one another whereby the drilling tool and 20 the feeding mechanism may be simultaneously controlled by the operator with the use of but one hand. Other objects and advantages of my invention will be apparent in the course of the following specification and 25 appended claims.

In the accompanying drawings, I have shown for purposes of illustration two forms which my invention may assume in practice.

In these drawings,

Fig. 1 is a view partially in elevation and partially broken away showing a drilling mechanism embodying my improved construction.

Fig. 2 is a transverse section on the line 40 2--2 of Fig. 1.

Fig. 3 is a section on the broken line 3--3 of Fig. 2.

Fig. 4 is a view showing one position of the valve and illustrating sections on the 45 lines a--a and b--b of Fig. 2.

Fig. 5 is a similar view with the parts in a different position.

Fig. 6 is a section corresponding to Fig. 2 and showing a modification.

For purposes of illustration I have shown 50 my improved feeding mechanism employed in connection with a percussive motor 1 of well known commercial form, which motor is adapted to impart a series of blows to a drill steel 2 and is maintained in proper

spaced relation to said drill steel as the hole is deepened by a feed mechanism 3. This feeding mechanism comprises a cylinder 4 having a bore 5 in which a piston 6 provided with a piston rod 7 is longitudinally reciprocable. The piston rod 7 is provided with a point 8 adapted to rest against a wall of a stope or some other suitable abutment and to, when it is held stationary, cause relative movements between the piston 6 and the cylinder 4 to take the form of movements of the cylinder 4 and drill 1 while the piston remains stationary. I have provided controlling mechanisms for the feeding mechanism and for the motor 1 comprising a chamber 9 formed in a member 10 interposed between the rear head of the motor 1 and the feeding mechanism 3. Disposed within the chamber 9 is a bushing 11 having a conical bore as indicated at 12 and rotatable within 60 said bore is a conical valve 13. The bushing 11 is traversed by a port 14 through which fluid is supplied for use in the motor 1 and by a port 15 leading to a passage 16 communicating with the forward end of the feed cylinder bore 4. The valve 13 which is conical in shape to fit the bore 12 of the bushing is hollow as indicated at 17 and communicates with a fluid supply line 18. Traversing the wall of the valve and communicating with the chamber 17 is a port 19 which is adapted to communicate with the port 14 when the valve is rotated by its handle 20. A bore 21 is formed coaxially 65 in the valve and communicates at its forward end by a small passage 22 with the chamber 17. Opening laterally from the bore 21 is a passage 23 communicating with a groove 24 extending longitudinally of the valve in the periphery thereof. This groove 70 communicates with a circumferentially extending groove 25 which is adapted to cooperate with the port 15. Means operative to connect the port 15 with a vent 26 is also formed in the periphery of the valve as indicated at 27. A valve 28 having a generally conical end and with laterally cut away portions at diametrically opposite sides as indicated at 29 is longitudinally reciprocable 75 but held from rotation in the bore 21, and is provided with a head 30 against which a spring 31 presses to maintain the valve in such position as to provide a free communication between the ports 22 and 23. A handle 32 pivoted at 33 on the main operating 80

55 60 65 70 75 80 85 90 95 100 105 110

handle 30 is adapted to, when squeezed by the operator, cause the closing of the valve 28 and interrupt the communication between the ports 22 and 23.

5 The mode of operation of this mechanism will be readily apparent. It will be evident that by turning the handle 20 the valve 12 will be caused to rotate in such manner as to bring about communication between the 10 groove 25 and the port 15 and also communication between the port 19 and the port 14. As a result the feeding mechanism will be placed in operation and the drill motor 1 started. If it is desired to interrupt the 15 feed, it will be evident that by squeezing the handle 32 toward the handle 20, this will be readily accomplished, as with no more air supplied to the front end of the feed cylinder leakage will tend to reduce the pressure 20 in the feeding mechanism and even were leakage to be entirely eliminated, but a short movement of the cylinder 4 relative to the piston 6 would be necessary before the pressure within the feed cylinder would drop 25 sufficiently due to expansion to practically eliminate pressure of the tool against the work. Also, if it be desired to regulate the pressure rather closely, this can be accomplished by momentarily opening the valve 30 28 only for such periods of time as will be necessary to maintain the desired pressure in the feeding mechanism.

In Fig. 6 I show another form which my 35 invention may assume in practice. In this case, the construction is identical with the exception of the fact that instead of being an end seating valve, the valve 28' is of the piston type and is prevented from rotating by any suitable means, and a passage 22' 40 having a lateral communication with the chamber 21 is controlled by a groove 34 which alternately connects the passage 22' with the port 23 or interrupts connection when the unbroken surface of the valve 28' 45 is brought opposite the radially extending portion of the port 22'. The mode of operation of this species of my invention is identical with that previously described, due allowance being made for the type of valve 50 employed.

While I have in this application specifically described two forms which my invention may assume in practice, it will be understood that these forms of the same are 55 shown for purposes of illustration and that the invention may be modified and embodied in other forms without departing from its spirit or the scope of the appended claims.

60 What I claim as new and desire to secure by Letters Patent is:—

1. A controlling valve mechanism for a 65 rock drilling motor and feeding means therefor comprising a casing having fluid passages formed therein leading respectively to said

motor and said feeding means, a main controlling valve arranged within said casing having an operating handle, said valve including means for controlling the fluid flow in said passages, and supplemental feed controlling means including a valve arranged coaxially within said main valve and reciprocable axially relative thereto for controlling the fluid flow in the passages leading to said feeding means, said valve having a controlling handle pivotally connected to said main valve operating handle to swing towards and from said handle and operating to close said supplemental valve when said handles are brought together. 70 75 80

2. A controlling valve mechanism for a rock drilling motor and feeding means therefor comprising a casing having fluid passages formed therein leading respectively to said motor and said feeding means, a main controlling valve arranged within said casing having fluid passages formed therein adapted to communicate with said fluid passages, said valve having an operating handle, and supplemental feed controlling means including a valve arranged coaxially within said main valve and reciprocable axially relative thereto for controlling the fluid in the passages leading to said feeding means, said valve having a controlling handle pivotally connected to said main valve operating handle to swing towards and from said handle and operating to close said supplemental valve when said handles are brought together and having means for automatically opening said valve when said handles are released. 90 95 100

3. In a pressure fed tool, the combination with a hammer drill and a pressure fluid feeding device attached thereto, of independently operable valves, one of which having means for controlling both the feeding mechanism and the tool and the other of which having means for controlling only the feeding mechanism, said valves having overlying handles one of which is rotatable to effect control of its valve and the other of which is movable in a plane at right angles to the plane of movement of said first mentioned handle. 110 115

4. In a pressure fed tool, the combination with a hammer drill, of a pressure fluid feeding device attached thereto, a rotatable valve having means for controlling the supply of motive fluid to said drill and to said feeding device, and a coaxially disposed valve having means for controlling the supply of pressure fluid to said feeding device only, said last mentioned valve being reciprocable axially with respect to said first mentioned valve. 120 125

5. In a pressure fed tool, the combination with a hammer drill, of a pressure fluid feeding device attached thereto, means including a valve and passages controlled 130

- thereby for controlling the operation of said drill and of said feeding device, operating means therefor, and auxiliary means for controlling said feeding device comprising a 5 valve and operating means therefor pivoted on said first mentioned operating means movable rotatably with said first mentioned operating means and likewise movable at right angles thereto.
- 10 6. In a pressure fed tool, the combination with a hammer drill, of a pressure fluid feeding device attached thereto, and means for controlling the fluid flow to said feeding device comprising coaxially disposed valves 15 both of which partake of movements in one direction and one of which is movable in an additional direction and passages controlled by said valves.
7. A drilling mechanism comprising a 20 drilling motor and pressure fluid feeding means therefor, a throttle valve provided with an operating handle adapted to be grasped by the operator, said valve having means for controlling said motor and said 25 feeding means, and supplemental controlling means for the feeding means including an element located in juxtaposition to said handle to enable the operator to control the pressure within said feeding means by the 30 hand grasping said handle and without removing said hand from said throttle valve handle.
8. A drilling mechanism comprising a drilling motor and pressure fluid feeding 35 means therefor, a throttle valve provided with an operating handle adapted to be grasped by the operator, said valve having means for controlling said motor and said feeding means, and supplemental feed 40 controlling means including a reciprocable valve having a manually operable actuating element located in juxtaposition to said handle for enabling the operator to control the pressure within said feeding means by 45 but a single hand without removing said hand from said throttle valve handle.
9. A drilling mechanism comprising a drilling motor and pressure fluid feeding 50 means therefor, a throttle valve provided with an operating handle adapted to be grasped by the operator, said valve having means for controlling said motor and said feeding means, and supplemental feed 55 controlling means including a reciprocable valve arranged coaxially within said throttle valve and having a manually operable actuating element located in juxtaposition to said handle for enabling the operator to control the pressure within said feeding means by 60 but a single hand without removing said hand from said throttle valve operating handle.
10. A drilling mechanism comprising a fluid actuated work performing and feeding 65 means, means including a rotatable
- valve and passage means controlled thereby for controlling the supply of motive fluid to both of said means provided with an operating handle adapted to be grasped by the operator, and a coaxially disposed valve for 70 controlling only the feeding means, said said last mentioned valve being reciprocable axially with respect to said other valve and so arranged with respect to said handle as to enable the operator to control the feed by 75 but a single hand without removing said hand from said valve operating handle.
11. A drilling mechanism comprising a drilling motor and pressure fluid feeding means therefor, control means extending 80 from said mechanism adapted to be grasped by the operator, and means for controlling said motor and feeding means including coaxial valves and a pivoted operating element forming parts of said control means, 85 said pivoted element being located adjacent the grasped portion of said control means for enabling the operator to control said motor and said feeding means by but a single hand without removing said hand 90 from said control means.
12. A drilling mechanism comprising a drilling motor and pressure fluid feeding means therefor, control means extending 95 from said mechanism adapted to be grasped by the operator, and means for controlling said motor and feeding means including relatively movable coaxial valves one of which is rotatable while the other is reciprocable, and a pivoted operating element forming 100 parts of said control means, said pivoted element being located adjacent the grasped portion of said control means for enabling the operator to control said motor and said feeding means by but a single hand without 105 removing said hand from said control means.
13. A drilling mechanism comprising a fluid actuated motor and feeding means, a main throttle valve having means for controlling the fluid flow to said motor and to 110 said feeding means, and supplemental feed controlling means for independently controlling the fluid flow to said feeding means including a longitudinally reciprocable valve arranged coaxially within said main valve. 115
14. A drilling mechanism comprising a fluid actuated drilling motor and pressure fluid feeding means therefor, a throttle valve having means for controlling the fluid flow to said motor and to said feeding means, and a supplemental feed controlling valve longitudinally reciprocable coaxially within said 120 throttle valve and operable independently thereof for controlling the pressure within said feeding means.
15. A drilling mechanism comprising a fluid actuated drilling motor and pressure fluid feeding means therefor, a throttle valve provided with a lever adapted to be grasped by the operator, said valve having means for 125
- 130

controlling the fluid flow to said motor and to said feeding means, and a supplemental feed controlling valve longitudinally reciprocable coaxially within said throttle valve and operable independently thereof and having an independent control element so arranged as to enable the operator to control the pressure within said feeding means by but a single hand without removing said hand from said throttle valve handle.

16. A drilling mechanism comprising a fluid actuated drilling motor and pressure fluid feeding means therefor, a throttle valve provided with a movable handle adapted to be grasped by the operator for controlling the fluid flow to said motor and to said means, and a supplemental feed controlling valve including operating means associated with said handle and so arranged with respect thereto as to enable the operator to control the feed with but a single hand without removing said hand from said handle.

17. A drilling mechanism comprising fluid actuated work performing and feeding means, independently operable valves, one of which has means for controlling both of said means and the other of which has means for controlling only the feeding means; said valves having overlying handles one of which is rotatable to effect control of its valve and the other of which is pivoted on said other handle and swingable relative thereto in a plane at right angles to the

plane of the movement of said other handle.

18. A drilling mechanism comprising fluid actuated work performing and feeding means, a valve having means for controlling both of said means and provided with an operating handle adapted to be grasped by the operator, and a valve having means for controlling only the feeding means, said valve being provided with an operating handle which overlies said other handle in proximity thereto to enable the operator to control the feed by but a single hand without removing said hand from said first mentioned handle.

19. A drilling mechanism comprising fluid actuated work performing and feeding means, a valve having means for controlling both of said means provided with an operating handle adapted to be grasped by the operator, and a valve having means for controlling only the feeding means, said valve being provided with an operating handle which overlies said other handle in proximity thereto and which is movable in a plane at right angles to the plane of movement of the other handle, the relative portions of said handles being such as to enable the operator to control the feed by but a single hand without removing said hand from said first mentioned handle.

In testimony whereof I affix my signature.

ELMER G. GARTIN.
